(57) **CLAIM**

The ornamental design for shapewear, as shown and described.

DESCRIPTION

FIG. 1 is a front, top perspective view of a shapewear, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded view of FIG. 1, showing the internal layer and outer layer being separated;

FIG. 10 is a rear, bottom perspective view thereof;

FIG. 11 is a front elevation view of the outer layer of the shapewear;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front elevation view of the internal layer of the shapewear;

FIG. 18 is a rear elevation view thereof;

FIG. 19 is a left side elevation view thereof;

FIG. 20 is a right side elevation view thereof;

FIG. 21 is a top plan view thereof; and,

FIG. 22 is a bottom plan view thereof.
